WATER METERING FLUSH VALVE
ASSEMBLYPat Romanelli and Charles Miller,
New York, N. Y.

Application August 10, 1950, Serial No. 178,610

6 Claims. (Cl. 137—667)

1

This invention relates to improvements in flush valve assemblies of the pressure-operated type adapted to discharge a metered amount of water.

The conventional meter-type flush valve assembly in use today is provided in buildings in which water is supplied under pressure, for use in flushing toilet bowls, urinals, or the like. The flush valve is provided with a handle or other manual operating means, which upon actuation causes the valve to discharge a specific measured amount of water to the toilet bowl or the like, automatically. This measured amount of water is a relatively large amount, and cannot be regulated by the user once the handle is actuated. Since, in many instances, only a small amount of water is required for flushing, the use of the conventional flush valve can be uneconomical and wasteful.

It is an object of this invention to provide an improved flush valve in which the usual large metered amount of water, or a smaller metered amount of water may be discharged for flushing at the selection of the user, upon the proper actuation of the operating handle.

Another object of the invention is the provision of a flush valve of the character described in which the large or small amounts of water are dispensed automatically upon proper selected actuation of the operating handle.

Other objects and advantages of the invention will be readily apparent in the course of the following specification when taken in connection with the accompanying drawings, in which:

Fig. 1 is a side elevational view of the improved flush valve assembly with portions thereof shown in vertical section, and the parts thereof shown in their inoperative position;

Fig. 2 is a side elevational view partially in section of a portion of the flush valve assembly, showing the parts thereof in a first operative position;

Fig. 3 is a side elevational view partially in section similar to Fig. 2, but showing the parts of the flush valve assembly in a second operative position; and

Fig. 4 is a front plan view of the handle assembly of the flush valve assembly in its position of Fig. 1.

Referring in detail to the drawings, and in particular to Fig. 1, there is shown a flush valve assembly of the balanced-valve type, incorporating the present invention.

The flush valve assembly comprises the conventional hollow casing 10 which is cast from heavy metal as an integral unit. The casing 10

2

includes a lateral inlet extension 11, a depending outlet extension 12, a lateral handle extension 13, and an integral discharge tube 14.

The discharge tube 14 extends vertically through the center of casing 10 from the upper end of said casing 10 to the outlet extension 12, and is open at both ends. The upper end of the discharge tube 14 is centrally spaced from the walls of casing 10, defining a pressure chamber 15 within casing 10. Said pressure chamber 15 is open at its top end, and also communicates with the inlet extension 11.

The casing 10 also contains a valve unit, which comprises a hollow metal pressure dome 16, a resilient diaphragm 17, a valve cylinder 18, and a poppet valve 19.

The pressure dome 16 is of sufficient size to seat upon the top open end of casing 10, covering the pressure chamber 15 and the discharge tube 14. The resilient diaphragm 17 is secured across the bottom of pressure dome 16 by cementing along its peripheral edge. Diaphragm 17 contains a circular central opening through which the valve cylinder 18 extends. Said valve cylinder

18 has an enlarged upper portion 18a which is sized to fit slidably within the discharge tube 14. The upper portion 18a contains in its top surface a well or recess 18b which serves as a valve seat. The valve seat 18b may have a rubber washer 20 fixed to its bottom surface, or may be lined with rubber.

The upper portion 18a of valve cylinder 18 also contains a circumferential groove or slot 21. The central opening of diaphragm 17 fits tightly around said groove 21 with the edges of said central opening secured within the circumferential groove, as by cementing, to provide a leak-proof seal.

In valve units of this type, the resilient diaphragm 17 is made of a flexible material such as rubber so that it is bendable and compressible.

The stem 19a of poppet valve 19 extends through the valve cylinder 18 and depends beyond the bottom of said valve cylinder 18. The head 19b of poppet valve 19 has a planar bottom surface, so that said head 19b lies flat within valve seat 18b, providing a water-tight seal across the top of valve cylinder 18.

A cap or cover member 22 is threadedly secured to the top of casing 10 in the usual manner. When cap 22 is turned to its secured position, it clamps the pressure dome 16 and its attached diaphragm 17 against the marginal upper edge of casing 10.

A metallic insert member 23 extends through

the wall of diaphragm 17. Said insert member 23 has a through-and-through bore 24 of small diameter.

The lateral inlet extension 11 is internally threaded for attachment of a conventional coupling unit 25 which includes a freely rotatable nut 26 by means of which the inlet extension 11 may be coupled to a water pipe leading to a suitable source of water supply. In valve units of this type, the water must be supplied under pressure.

The outlet extension 12 bears a threaded nut 27 which is adapted to compress a resilient washer 28 for coupling said outlet extension to a pipe leading to the bowl of a toilet or the like.

Thus far, the construction of the flush valve assembly previously described, is conventional and well known. The conventional flush unit is adapted to permit the flow of a predetermined, metered amount of water through discharge tube 14, upon actuation of a handle which is mounted in handle extension 13 by a ball joint. When the handle is pivoted in any direction, the poppet valve 19 is tilted, and a metered amount of water is discharged, this metered amount of water being dependent upon the size of the bore 24 in insert 23 of diaphragm 17, and therefore, being constant every time the handle is actuated. There is, therefore, no manner in which the user may discharge a lesser amount of water, since the entire metered amount will be discharged automatically upon actuation of the handle.

The present invention comprises a novel valve and handle structure, which co-act to enable the user to selectively dispense a metered amount of water of the usual large quantity, or a lesser metered amount of water, the selection being made by pivoting the handle in either an upward or downward direction.

The outer surface of handle extension 13 is threaded to receive a nut 30 which rigidly couples a tubular handle casing 31 to said handle extension 13. The handle casing 31 contains the hemispherical inner end portion 32 of the handle member 33. The outer end of handle member 33 extends exteriorly of handle casing 31, and is located for manual actuation. A horizontal pivot pin 34 pivotally connects the inner end portion 32 of handle member 33 to the handle casing 31, so that said handle member 33 is pivotable only in a vertical direction. The hemispherical inner end portion 32 has a planar end surface 32a.

A guide block 35 fits within the open outer end of handle extension 13. This guide block 35 has a peripheral flange 36 adjacent its outer end which abuts the outer front surface of handle extension 13, and is held rigidly in this position by the inward clamping pressure of nut 30 upon handle casing 31. The guide block 35 has an outer cylindrical extension 37 extending outwardly beyond the peripheral flange 36, said extension 37 being externally threaded for coupling to matching internal threading of the handle casing 31.

In the assembled position of the handle unit, a washer 38 may be interposed between the peripheral flange 36 of guide block 35 and the outer surface of handle extension 13.

The guide block contains a pair of vertically-alined cylindrical bores 40 and 41. Said bores 40 and 41 contain respective cylindrical tilt pins 42 and 43 which are slidable therein. Each of said tilt pins 42 and 43 has an enlarged head 44 which has a planar outer surface. A pair of compression springs 45 and 46 encircle the outer ends of the respective tilt pins 42 and 43 between

the guide block 35 and the pin heads 44, said springs 45 and 46 urging the heads 44 of the respective pins 42 and 43 away from said guide block 35 and into flat abutment with the planar end surface 32a of handle 33.

The pressure of both springs 45 and 46 is also sufficient to maintain the handle member 33 in its normal inoperative horizontal position shown in Fig. 1.

The inner ends of tilt pins 42 and 43 in their inoperative positions of Fig. 1, abut the lower end of the stem 19a of poppet valve 19, or are slightly spaced from the stem 19a.

A yoke-shaped latch 47 is coupled to the lower tilt pin 43. As shown in Fig. 4, the legs of said latch 47 straddle the pins 42 and 43 and are pivotally attached to pin 43 by a pivot pin 48. The latch 47 has a notched portion 49 which forms a lateral upper terminal latch tooth 50. This latch tooth 50 has a central recess or opening 51, shown in Fig. 4.

The uppermost tilt pin 42 bears a rigidly-fixed sleeve or ring 52 which is positioned to abut the front surface of the latch 47 in the inoperative position of the tilt pins 42 and 43 shown in Fig. 1. The inner edge of guide block 35 has a lateral protuberance 53 which abuts the rear inner surface of latch 47.

A vertical by-pass bore 54 of small diameter extends through the enlarged upper portion 18a of valve cylinder 18, and through the diaphragm 17. Said by-pass bore 54 connects the pressure dome 16 with the interior of discharge tube 14.

The valve cylinder 18 is of appreciably lesser diameter than the discharge tube 14. Said valve cylinder 18 is preferably provided with spaced lateral vanes 55 which maintain said valve cylinder 18 in a centered position within discharge tube 14. A needle valve assembly is mounted on the outer wall of valve cylinder 18 between said vanes 55 and beneath by-pass bore 54. This valve assembly comprises a vertical needle valve 56 which is slidably mounted in brackets 57 which are integral with or rigidly fixed to the outer wall of valve cylinder 18. The needle valve 56 has a lateral projection or pin 58, and a lug 59 at its bottom end. A compression spring 60 is interposed between the pin 58 and the lowermost bracket 57, said spring 60 urging the needle valve 56 to an upward position in which the point of needle valve 56 is located within and closes off the bottom end of by-pass bore 54.

The lug 59 of needle valve 56 is normally located in a position in which the latch tooth 50 engages said lug 59, as shown in Fig. 1. When the latch 47 is pivoted forwardly, as shown in Fig. 3, the latch tooth 50 remains in engagement with the lug 59, the stem of needle valve 56 sliding within the central opening 51 of latch tooth 50. When the latch 47 is pivoted rearwardly, as shown in Fig. 2, the latch tooth 50 is brought out of engagement with lug 59.

In the normal inoperative position of the flush valve assembly shown in Fig. 1, water is supplied under pressure to inlet extension 11, said water filling the pressure chamber 15. The pressure dome 16 is also filled with water, this water communicating with the water in pressure chamber 15 through the bore 24 of diaphragm insert 23, so that the water pressure within pressure dome 16 is equal to the water pressure in pressure chamber 15. This water pressure in pressure dome 16 bears against the top surface of poppet valve head 19b, pressing said valve head 19b to a

firm seated position in valve seat 18b. Pressure on valve head 19b also depresses the valve cylinder 18 and the center of diaphragm 17, so that the central bottom surface of diaphragm 17 presses against the top surface of discharge tube 14, providing a water-tight seal thereabout. In this inoperative position, therefore, water cannot escape from the pressure chamber 15 through the discharge tube 14 or from the pressure dome 16 through the valve cylinder 18.

In order to dispense the normal metered amount of water through the valve assembly, the handle member 33 is pivoted downwardly as shown in Fig. 2. The planar end surface 32a of handle member 33 bears against the head 44 of lower tilt pin 43 and slides said tilt pin 43 inwardly through the bore 41 of guide block 35, against the tension of compression spring 46. The lower end of the latch 47 moves inwardly with the tilt pin 42, and since the upper end of latch 47 is held from forward movement by the ring 52 of upper tilt pin 42, the latch 47 is pivoted rearwardly on pivot pin 48 to a position in which latch tooth 59 is held well spaced from the lug 59 of needle valve 56. The spring 60 therefore maintains the point of needle valve 56 in the bottom of by-pass bore 54, so that water cannot escape from pressure dome 16 through said by-pass bore 54.

When the lower tilt pin 43 is slid inwardly, it strikes the lower end of poppet valve stem 19a tilting the poppet valve 19 so that its head 21 is tilted in valve seat 18b. The head pressure in pressure dome 16 is thus broken as water flows from pressure dome 16 through the valve seat 18b and into valve cylinder 18. The pressure of the water in pressure chamber 15 is now greater than the pressure in pressure dome 16, so that this water pressure against the bottom surface of resilient diaphragm 17, raises the central portion of diaphragm 17 out of sealed engagement with the top rim of discharge tube 14, and also raises the enlarged upper portion 18a of valve cylinder 18 out of the discharge tube 14. The water supplied under pressure through the inlet extension 11 is now free to flow through pressure chamber 15 directly into the top of discharge tube 14 and through said discharge tube to a toilet bowl or the like.

When the operating handle 33 is released, pressure of spring 46 will bring the lower tilt pin 43 to its normal position of Fig. 1, in which its head 44 is aligned with the head of upper tilt pin 42, thus bringing the operating handle 33 to its inoperative horizontal position. The lower tilt pin 43 also moves out of contact with valve stem 19a, enabling poppet valve 19 to straighten by its own weight so that valve head 19b is again flatly seated in valve seat 18b. As water flows through pressure chamber 15, some of this water enters the pressure dome 16 through bore 24 of diaphragm insert 23, so that the pressure dome 16 gradually fills up. When the pressure dome 16 is completely filled, its internal water pressure is the same as the water pressure in pressure chamber 15, and the valve cylinder 18 and resilient diaphragm 17 are again lowered until the diaphragm 17 seals the top of discharge pipe 18 and halts the flow of water therethrough.

The aforementioned operation is typical of the normal metered operation of a conventional flush valve assembly, the amount of water discharged being dependent upon the size of the bore 24 in diaphragm insert 23. The smaller the bore 24, the longer the time consumed in refilling the pressure

dome 16, and the longer the time in which water flows through discharge tube 14.

When a smaller metered amount of water is desired to be dispensed, the operating handle 33 is pivoted upwardly, as shown in Fig. 3, so that its planar end surface 32a presses the head 44 of upper tilt pin 42 inwardly, and moves away from the head 44 of lower tilt pin 43, allowing compression spring 46 to bias lower tilt pin 43 outwardly relative to guide block 35. For this purpose, the top end of head 44 of lower tilt pin 43 may be bevelled as shown at 61 in Figs. 2 and 3. The inward movement of upper tilt pin 42 tilts the poppet valve 19 in the manner previously described, and also moves the ring 52 out of contact with the latch 47. The rearward movement of lower tilt pin 43 moves the lower end of latch 47 rearwardly, causing said latch to pivot forwardly, as shown in Fig. 3, the lug 59 of needle valve 56 extending well within the notch 49 of latch 47.

As the poppet valve 19 is tilted, the head pressure in pressure dome 16 is broken, as previously described, and the pressure of the water in the pressure chamber 15 lifts the diaphragm 17 and valve cylinder 18, enabling water to flow through discharge tube 14. Since the needle valve lug 59 is engaged by latch tooth 50, the valve cylinder 18 rises relative to the needle valve 56, bringing the by-pass bore 54 out of contact with the point of said needle valve 56, said needle valve 56 being held in a downward position against the tension of spring 60. The water flowing through pressure chamber 15 may now enter the pressure dome 16 through the by-pass bore 54, as well as through the bore 24 of insert 23. The pressure dome 16 may therefore refill more quickly than in the normal operation, with the result that the top of discharge tube 14 is closed off more quickly by diaphragm 17, and a lesser amount of water is discharged through discharge tube 14. This amount may be regulated by varying the size of by-pass bore 54.

When the handle 33 is released, the tilt pins 42 and 43 take their normal aligned positions of Fig. 1, the latch 47 pivoting to its vertical position, but still engaging the needle valve lug 59 and holding needle valve 56 in its downward position. When the pressure dome 16 completely refills, and the diaphragm 17 and valve cylinder 18 are lowered to close off the top of discharge tube 14, as shown in Fig. 1, the by-pass bore 54 is lowered into contact with the point of needle valve 56, and the entire valve assembly is again in its inoperative position.

While a preferred embodiment of our invention has been shown and described herein, it is obvious that numerous additions, changes, and omissions may be made in the invention without departing from the spirit and scope thereof.

What is claimed is:

1. A flush valve assembly comprising a housing having a water inlet and a water outlet, a resilient diaphragm normally closing off said water outlet, manual operating means adapted to regulate water pressure within said housing in order to move said diaphragm and enable water to flow from said water inlet to said water outlet, valve means regulated by said manual operating means, said diaphragm having an unobstructed opening therein adapted to equalize water pressure within the casing in order to return said diaphragm to its closed position, said diaphragm also having a by-pass opening which is normally closed by said valve means and which is opened

when said valve means is actuated, said manual operating means being adapted to be brought to a first operative position and a second operative position, and connecting means coupled to said operating means and movable into contact with said valve means for actuation thereof when said operating means is brought to its first operative position, and out of contact with said valve means when said operating means is brought to its second operative position.

2. A flush valve assembly comprising a housing having a water inlet adapted to be connected to a source of water under pressure, a water outlet, a resilient diaphragm normally maintained by the pressure of water thereabove in a position in which it closes off said water outlet, a valve unit adapted to be actuated to release the water pressure above said diaphragm to enable the water pressure below said diaphragm to raise said diaphragm out of its sealed relation with said water outlet, whereby water is free to flow from said water inlet to said water outlet, operating means adapted to be selectively brought to a first operating position and to a second operating position in which positions said valve unit is actuated, said diaphragm having an opening positioned to equalize the water pressure above and below said diaphragm to cause said diaphragm to settle to its closed position, said diaphragm also having an auxiliary opening, said flush valve assembly also having movable valve means normally biased into sealing engagement said auxiliary opening, said operating means having a detent member movably mounted to engage and hold said valve means spaced from said auxiliary opening when said operating means is brought to only one of its operating positions.

3. A flush valve assembly having a housing which has a water outlet and a water inlet adapted to be connected to a source of water under pressure, a resilient diaphragm normally held by the pressure of water thereabove in a position in which it covers said water outlet, a poppet valve associated with said diaphragm and adapted to be tilted to release said water pressure above said diaphragm and cause the water pressure below said diaphragm to raise said diaphragm and uncover said water outlet, an operating handle pivotally mounted on said housing and adapted to be brought to an upward and a downward operative position, means connecting said operating handle with said poppet valve, said connecting means being adapted to tilt said poppet valve in both operative positions of said handle, said diaphragm having an opening sized and positioned to equalize the water pressure above and below said diaphragm to cause said

diaphragm to return to its closed position in a selected period of time, said diaphragm also having an auxiliary opening, said flush valve assembly having a needle valve which is normally biased to a position in which it closes said auxiliary opening, and latch means coupled to said connecting means and movable thereby to engage and hold said needle valve out of engagement with said auxiliary opening when said handle is brought to its upward operative position, whereby the diaphragm presents two openings to enable the water pressure in said housing to equalize in less than said selected period of time, said latch means being rendered inoperative by said connecting means when said handle is brought to its downward operating position.

4. A flush valve assembly according to claim 3 in which the connecting means comprises a pair of tilt pins slidably mounted in said housing in vertical alinement with each other, said handle member having a planar inner surface which abuts the outer ends of said tilt pins, the inner surface of said operating handle being adapted to press the upper tilt pin inwardly within said casing when said operating handle is pivoted upwardly, and to pivot the lower tilt pin inwardly when said operating handle is pivoted downwardly, the inner ends of said tilt pins being located adjacent said poppet valve, whereby said poppet valve is tilted when one of said pins is pressed inwardly.

5. A flush valve assembly according to claim 4 in which the latch means is pivotally mounted on said lower tilt pin and in which means are provided to pivot said latch means rearwardly out of latched engagement with the needle valve when said lower tilt pin is pressed inwardly.

6. A flush valve assembly according to claim 4 in which the tilt pins are biased outwardly to a normal inoperative position in which they abut the planar inner surface of the operating handle, said latch means being pivotally mounted on said lower tilt pin, said upper tilt pin having a projection which abuts the front end of said latch means in the normal inoperative positions of said tilt pins.
